[57] CLAIM

The ornamental design for a chair, as shown and described.

DESCRIPTION

FIG. 1 is a front elevational view of the chair showing my new design,

FIG. 2 is a side elevational view,

FIG. 3 is a top plan view,

FIG. 4 is the opposite side elevational view to that shown in FIG. 2,

FIG. 5 is a rear elevational view; and

FIG. 6 is a bottom plan view thereof.

The dot-dash lines simulating a stylized version of a head in FIGS. 1-6 have been shown for illustrative purposes.
